MICROFILM RECORDER FOR COMPUTER DATA

Jay Sucre, Exton, Pa., William A. Hoffman, Collingswood, N.J., and Nazareno D. Marucci, Philadelphia, Pa., assignors to Burroughs Corporation, Detroit, Mich.

Filed June 12, 1969, Ser. No. 17,673

Term of patent 14 years

Int. Cl. D14—02

U.S. Cl. D26—5

The figure is a front perspective view taken from one side of a microfilm recorder for computer data embodying our new design, the opposite side being a mirror image of the side shown and the rear being plain and unornamented.

We claim:

The ornamental design for a microfilm recorder for computer data, substantially as shown and described.
